PERCUSSION FUSE

Marc Birkigt, Bois-Colombes, France

Application March 27, 1936, Serial No. 71,327
In Belgium January 18, 1936

6 Claims. (Cl. 102—39)

The present invention relates to percussion fuses for projectiles rotating about their axis along their trajectory and it is more especially, although not exclusively, concerned with fuses of this kind for projectiles of small calibre.

The object of the present invention is to provide a fuse of this kind which is better adapted to meet the requirements of practice than similar fuses made up to the present time.

The essential feature of the present invention consists in providing balls or the like for locking the striker of the fuse as long as it is necessary, and in providing, around said balls, a chamber the walls of which are in the shape of a body of revolution, having notches formed therein for accommodating the balls, which can thus move out of locking engagement with the striker, the whole being arranged in such manner that the balls, which turn with respect to said walls under the effect of the rotary movement of the projectile can penetrate into these notches only when the speed of said balls is little different from that of the wall of said chamber.

Other features of the present invention will result from the following detailed description of a specific embodiment thereof.

A preferred embodiment of the present invention will be hereinafter described, with reference to the accompanying drawing, given merely by way of example, and in which:

Fig. 1 is an axial sectional view of a percussion fuse according to the present invention;

Figs. 2, 3 and 4 are views, similar to Fig. 1, showing the parts in different relative characteristic positions thereof;

Fig. 5 is a perspective view of one of the elements of the fuse;

Fig. 6 is a sectional view on the line II—II of Fig. 2;

Fig. 7 is a sectional view on the line III—III of Fig. 3.

The invention will be described in detail with reference to a fuse for a shell intended for a gun the tube of which is provided with riflings.

The principle of the invention consists in locking the striker of the fuse by means of balls enclosed inside a cage which prevents them from escaping radially, said balls releasing said striker when they are allowed to move away from said striker to a certain distance therefrom.

According to the invention, said cage is provided with notches into which the balls can penetrate, but only after their speed of revolution about the axis of the projectile has reached a

value approximating the speed of revolution of the cage.

It will be readily understood that, immediately after the shot has been fired and as long as the speed of revolution of the balls about the axis of the projectile is substantially lower than the speed of revolution of the cage, the notches move too quickly past the balls for permitting them to penetrate thereinto.

On the contrary, when the relative movement of the balls and the notches is slowed down, the balls can enter said notches and release the striker of the fuse.

This device is advantageously made in the following manner:

Concerning first the body of the fuse, it consists of a hollow metallic part 1 which is prolonged rearwardly, in the usual manner, so as to form a chamber 2 in which are placed the detonator 3 and the priming charge 4. This chamber is closed by a stationary piece 5, in the center of which there is provided an orifice 6, through which a striker 7 is slidably guided.

The front part of body 1 is hollowed out so as to form a chamber 8 communicating, at its front part with an axial bore 9, closed, at the front part, by a small plate 10.

The striker 7 includes, on the one hand, a head 11 adapted to slide in bore 9, and, on the other hand, an enlarged portion 12, located for instance in the intermediate part of said striker, said enlarged portion forming a stop adapted to cooperate with locking balls 13.

I further provide, in chamber 8, an element capable of preventing a rearward displacement of the balls, said element consisting, for instance, as shown by the drawing, of a cylindrical sleeve 14 carried by piece 5 and the front edge of which is of conical shape, with an apical angle of say 120°.

Furthermore, I provide means whereby the balls are held between enlarged portion 12 and sleeve 14 before the shot is fired, whereas, immediately after the shot has been fired, the notches adapted to cooperate with said balls are brought opposite said balls.

These means may be devised as follows:

Chamber 8 is made of a shape such that its lateral wall surrounds, with a slight peripheral clearance space, balls 13 in the locking position thereof, notches 15 being provided in said wall opposite said balls. Between balls 13 and said wall, there is interposed a partition, either adapted to be easily torn (paper, tin sheet) or adapted

to be moved out of the way when the shot is fired, under the effect of inertia.

Such a partition would suffice to keep the balls in locking position under normal conditions and 5 would leave them free to move away under the effect of the centrifugal force.

However, I deem it preferable to employ the arrangement shown by the drawing.

In this case, there is provided, in chamber 8 10 behind bore 9, a longitudinal housing 16, for instance at least partly cylindrical and which may extend rearwardly around sleeve 14. In any case, the enlarged portion 12 of the striker must be located in the front part of said housing 16 (Figs. 15 1 to 3).

In this housing 16 there is housed a ring-shaped member 17, preferably cylindrical and of uniform thickness, securely but elastically held in said housing. For instance, as shown by Fig. 5, said 20 ring-shaped member is slit, and it is given a size such that it is necessary to contract it from inserting it into housing 16. The friction thus produced is sufficient for preventing any displacement of said member 17 in housing 16 as 25 long as said member is not urged by an enormous force, such as that which acts on the parts when the shot is fired.

This ring-shaped member 17 is made of such a height and thickness that, on the one hand, in 30 its front position (Fig. 1), which it is given when the parts are assembled, its rear part is located in the same transverse plane of the balls when the latter are located between sleeve 14 and enlarged part 12, thus keeping said balls in the locking 35 position, and, on the other hand, in its rear position (Figs. 2 to 4), said member 17 has its front part in the same transverse plane as the balls, which it would still keep in the locking position if said front part of member 17 were not 40 especially devised.

This front part of member 17 is provided with notches 15 such that, in the rear position of member 17, said notches are in the same transverse plane as balls 13 for the locking position 45 of said balls. These notches are made of such a size that a ball 13 can freely enter into each of them and that, after having entered said notches, said balls can move out therefrom toward the front of the front edge of ring 17, by moving 50 around the edge of enlarged portion 12 of the striker.

Advantageously, the device above described is completed by providing, in housing 16, a peripheral groove 18 devised in such manner that, after 55 passing through the notches, balls 13, instead of coming into contact with a cylindrical wall, meet a conical wall, of an apical angle of say 60°, along which they roll and simultaneously move toward the front, under the effect of the centrifugal force, 60 so as to finally reach (Fig. 4) the front portion, of larger diameter, of said groove 18.

The operation of a fuse as above described, the various parts of which are arranged, in the position of rest (corresponding to the locking of the 65 striker) as shown by Fig. 1, takes place as follows:

When the shot is fired, ring shaped member 17 moves in a rearward direction (Fig. 2) and the notches are brought into the transverse plane 70 of the balls, said balls being, due to the enormous acceleration imparted to the shell in the gun, strongly applied against the conical upper edge of sleeve 14, and therefore urged toward the axis of the fuse.

When the acceleration ceases, that is to say 75

after the shell has left the gun, the balls come into contact with ring-shaped member 17 (Fig. 6) but, while said member rotates with a speed of revolution equal to that of the projectile, said balls turn at a much lower rate, due to their inertia, and therefore they roll inside ring-shaped member 17 without being able to enter the notches, due to the difference between the speeds of rotation.

However, the speed of revolution of the balls increases owing to their friction against the projecting parts existing between the notches 15 and after a short time, the speed of revolution of the balls approximates that of ring-shaped member 17.

Then (Figs. 3 and 7), all the balls penetrate into corresponding notches and being urged forwardly due to the slowing down of the movement of the projectile along its trajectory and also to the conical shape of the sleeve 14, they move toward the front beyond the enlarged portion 12 of the striker, after having caused the latter to move slightly forwardly.

The striker is then released and when the shell meets with an obstacle, said striker is free to act 25 on the detonator.

It will be readily understood that the time necessary for releasing the striker determines the margin of safety. This time may be varied by acting, among other things, on the mass of 30 the balls, the number of said balls, the width of the notches, which may be substantially greater than the diameter of the balls and the shape of the solid parts extending between said notches. It is therefore possible to adjust at will 35 the distance from which, after having left the gun, the shell shall be capable of exploding.

Advantageously, the number of balls is equal to the number of notches (for instance four), but the number of said elements might be 40 different.

In a general way, while I have, in the above description, disclosed what I deem to be a practical and efficient embodiment of the present invention, it should be well understood that I do 45 not wish to be limited thereto as there might be changes made in the arrangement, disposition and form of the parts without departing from the principle of the present invention as comprehended within the scope of the appended 50 claims.

What I claim is:

1. A fuse for a projectile intended to move along its trajectory with a rotary movement about said trajectory which comprises, in combination, a fuse body, a detonator carried by said body, an axial striker movable in said body for action on said detonator, an annular element rigid angularly with said body coaxially surrounding said striker, a plurality of members normally applied against said striker so as to lock it in a position out of contact with said detonator, said members being adapted to run with a rolling movement on the inner wall of said element, said element being provided with a plurality of recesses adapted to accommodate said members so as to permit said members to move radially away from said striker and thus to unlock it, whereby said unlocking action takes place only when, due to frictions, said members roll inside said element at a speed approximating the speed of revolution of said fuse about its axis.

2. A fuse for a projectile intended to move along its trajectory with a rotary movement about said trajectory which comprises, in com- 75

- bination, a fuse body, a detonator carried by said body, an axial striker movable in said body for action on said detonator, an annular element, rigid angularly with said body, coaxially surrounding said striker, a plurality of members adapted to operatively engage said striker for locking it in a position out of contact with said detonator, means for keeping said members in the locking position thereof, adapted to be brought out of action by the acceleration undergone by said projectile when it is fired, said members being adapted to run with a rolling movement on the inner wall of said element, said element being provided with a plurality of recesses adapted to accommodate said members so as to permit said members to move radially away from said striker and thus to unlock it, whereby said unlocking action takes place only when, due to frictions, said members roll inside said element with a speed of revolution about the axis of the fuse approximating the speed of revolution of said fuse about its axis.
3. A fuse for a projectile intended to move along its trajectory with a rotary movement about said trajectory which comprises, in combination, a fuse body, a detonator carried by said body, an axial striker movable in said body for action on said detonator, an annular element, rigid angularly in said body and movable axially with respect thereto, coaxially surrounding said striker, a plurality of balls between said striker and said element adapted to operatively engage said striker, stop means for preventing rearward movement of said balls, whereby said balls, when engaged with said striker, lock it in a position out of contact with said detonator, said annular element fitting with a considerable amount of friction inside said housing in a normal position such that the solid rear part of said element keeps said balls in operative engagement with said striker, said annular element being provided with notches in its front part adapted to come into the same transverse plane as said balls when said element is displaced by inertia in said housing into its rear position, said notches being adapted to accommodate said balls so as to permit them to move radially away from said striker and thus to unlock it, whereby said unlocking action takes place only when, due to frictions, said balls roll inside said annular element with a speed of revolution about the axis of the fuse approximating the speed of revolution of said fuse itself.
4. A fuse according to claim 3 in which said stop means for preventing rearward movement of said balls consist of a sleeve rigid with said body and the front edge of which is bevelled so as to form an annular cup-shaped bearing for the balls.
5. A fuse according to claim 3 in which said annular element consists of a sleeve, slit longitudinally, mounted with a force fit inside said body.
6. A fuse according to claim 3 in which said body is provided with a chamber having conically divergent walls extending ahead of said notches, whereby said balls after passing into said notches escape frontwardly along the conical walls of said chamber.
